UNITED STATES PATENT OFFICE.

SAMUEL MILNE BUCHAN AND CARLYLE BUCHAN, OF PORTOBELLO, SCOTLAND.

DESIGN FOR A FLOWER HOLDER OR SIMILAR ARTICLE.

Application filed January 12, 1926, Serial No. 16,037, and in Great Britain September 16, 1925. Term of patent 14 years.

To all whom it may concern:

Be it known that we, SAMUEL MILNE BUCHAN and CARLYLE BUCHAN, subjects of the King of the United Kingdom of Great Britain, residing at Portobello, in the county of Midlothian, Scotland, have invented a new, original, and ornamental Design for a Flower Holder or Similar Article, of which the following is a specification, reference being had to the accompanying drawing, forming part thereof.

Fig. 1 is a side elevation of the flower holder, showing my new design and Fig. 2 is a vertical cross section thereof.

We claim:—

The ornamental design for a flower holder or similar article as shown.

SAMUEL MILNE BUCHAN.
CARLYLE BUCHAN.
